UNITED STATES PATENT OFFICE.

KATHARINE L. GRANT, OF NEW YORK, N. Y.

DESIGN FOR A BADGE, BROOCH, STICK-PIN, RING, WATCH-FOB, BUTTON, OR SIMILAR ARTICLE OF JEWELRY.

48,890.

Specification for Design. Patented Apr. 18, 1916.

Application filed October 28, 1915. Serial No. 58,508. Term of patent 7 years.

To all whom it may concern:

Be it known that I, KATHARINE L. GRANT, a citizen of the United States, residing in the city, county, and State of New York, have invented a new, original, and ornamental Design for a Badge, Brooch, Stick-Pin, Ring, Watch-Fob, Button, or Similar Article of Jewelry, of which the following is a specification, reference being had to the accompanying drawing, forming part hereof.

The figure of the drawing is a plan view of a badge illustrating my new design.

I claim—

The ornamental design for a badge, brooch, stick-pin, ring, watch-fob, button or similar article of jewelry, as shown.

KATHARINE L. GRANT.

In presence of—

RUSSELL W. TODD,
M. M. KLOS.
